UNITED STATES PATENT OFFICE

122,411

DESIGN FOR A DUST BRUSH FOR VENETIAN BLINDS

Gus M. Marks and Fred W. Carstens,
Oakland, Calif.

Application May 26, 1939, Serial No. 85,211

Term of patent 14 years

To all whom it may concern:

Be it known that we, Gus M. Marks and Fred W. Carstens, both citizens of the United States and residents of Oakland, in the county of Alameda and State of California, have invented a new, original, and ornamental Design for a Dust Brush for Venetian Blinds, of which the following is a specification, reference being had to the accompanying drawing, forming part thereof, wherein

Figure 1 is a perspective view of a dust brush for Venetian blinds embodying our new design.

Figure 2 is a top plan view of the brush.

We claim:

The ornamental design for a dust brush for Venetian blinds, substantially as shown.

GUS M. MARKS.
FRED W. CARSTENS.
